UNITED STATES PATENT OFFICE.

CHRISTIAN AUGUSTUS ALBRECHT, OF BERLIN, GERMANY, ASSIGNOR TO MERGEN-
THALER LINOTYPE COMPANY, A CORPORATION OF NEW YORK.

GALLEY MECHANISM FOR REPEATING AND NON-REPEATING LINE-CASTING MACHINES.

1,153,880.

Specification of Letters Patent. Patented Sept. 21, 1915.

Application filed May 18, 1914. Serial No. 839,185.

To all whom it may concern:

Be it known that I, CHRISTIAN AUGUSTUS ALBRECHT, a citizen of the United States of America, at present residing at Chausseestrasse 23, Berlin, N. 4, in the Empire of Germany, have invented new and useful Improved Galley Mechanism for Repeating and Non-Repeating Line-Casting Machines, of which the following is a specification.

10 This invention relates to an improvement in or modification of the invention described and claimed in the United States Letters Patent No. 1,085,567, to Hartmann and Schimmel. That patent was on a galley mechanism for a full measure line-casting typographical machine capable of casting a series of full measure lines from the same mold and having a single ejector to eject one such line at a time into a single galley, characterized by automatic means for effecting the ordination of all the lines into columns according to the copy, and also on the same mechanism characterized by means for limiting the casting to single lines from successively different molds, which lines are successively delivered into a single galley. But the automatic means consisted of an adjustable chute and a series of fixed galleys. But the construction of some composing machines makes an adjustable chute in the circumstances and for the purpose inconvenient and more or less impracticable.

35 The present invention consists in transferring the adjustability from the chute to the series of galleys, abandoning the series of fixed chutes of the above mentioned Letters Patent and connecting the series of galleys to some moving member of the machine, in such a way that one or two or more may 40 be put successively in register with the (now) fixed chute.

45 Referring to the drawings:—Figure 1 is a front view of a portion of a linotype machine having my invention applied thereto; Figs. 2, 3, 4 and 5 are detail-views; and Fig. 6 is a skeleton view showing the relation of some of the parts.

50 As usual in linotype machines, the composed line of matrices is transferred through the intermediate channel 11 into the first elevator 8, which is mounted to slide up and down in suitable guideways in the so-called vise frame 9. When the elevator receives the composed line it descends to present the

line in front of a slotted mold, wherein the 55 slug or linotype 1 is cast, and thereafter the elevator rises to forward the line for distribution, all as well understood. After the slug is cast the mold is brought by its carrier 12 opposite an ejector, which removes 60 the slug therefrom and carries it between a pair of trimming knives mounted on the vise frame and finally through a "port" opening 10 leading to the galley mechanism. All the parts so far described are or may be 65 as illustrated in U. S. Letters Patent No. 436,532 to O. Mergenthaler, or as embodied in the commercial linotype machine. In the use of these machines, it is common to cast 70 duplicate slugs from a composed line, suitable mechanism being provided to cause the line to be presented to the mold the requisite number of times for this purpose. It thus becomes desirable to keep the duplicate slugs separated, that is, to arrange them in 75 different columns, instead of in the same column. This result is accomplished in the Hartmann and Schimmel patent above referred to by providing the machine with a plurality of fixed galleys and with an adjustable chute or switch by which the duplicate slugs may be delivered successively 80 to the different galleys. However, as previously stated, this particular form of mechanism is not entirely suitable or practicable 85 in certain kinds or constructions of machines, and the present invention is therefore intended to overcome this difficulty. This object, it has been found, may be attained by arranging the plurality of galleys 90 so that they may be moved relatively to the other parts, instead of being fixed as heretofore.

Referring now in detail to my improved construction, it will be noted that the slugs 95 1, as they are ejected from the mold, drop into a fixed chute 2, which delivers them to one or another of the galleys 3, 4 and 5, the latter being supported by a slide 6 which is adjustable vertically in suitable guideways 100 in the vise frame 9 so that any selected one of the galleys may be brought into operative relation to the delivery chute 2. In the normal operation of the machine, the upper galley 3 remains in constant operative relation to the chute 2, but when the machine 105 is made to cast duplicate slugs from the same composed line, the galleys are adjusted

vertically so that a different one is brought into action after the casting of each of the duplicate slugs. The mechanism for effecting this adjustment of the galleys is controlled by the first elevator 8 and is shown in detail in Figs. 2, 3, 4 and 5. Referring to these figures, it will be noted that the slide 6 is connected to an arm 7 fast upon one end of a transverse rock shaft 16, which is mounted to turn in bearings in a supporting plate 15 fixed to the vise frame 9. At its opposite end the rock shaft 16 is provided with a sector 18 formed with tooth projections 19, which are adapted to be engaged by a finger 23 secured to the first elevator 8. In the normal position of the parts the sector 18 is held in a horizontal position, as shown in Fig. 5, by a pin 31 and with its upper tooth 19 in position to be engaged by the finger 23. As a result, when the first elevator 8 makes an ascent its finger 23 will engage the upper tooth 19 of the sector and rock it upwardly, thus bringing the second galley 4 into action; and on the next ascent of the elevator its finger 23 will engage the second tooth 19 and rock the sector upwardly further to bring into action the third galley 5. In order to hold the galleys in the different positions just described, there is provided a bar or detent 21 supported in the plate 15 and urged to the left, as shown in Fig. 2, by a spring 22, which bar is adapted to engage beneath one or the other of two lugs 20 fixed to the inner face of the sector 18, the lugs being arranged so that they will be brought successively into engaging relation as the sector 18 is rocked upwardly by the first elevator. When the galleys have been raised to their uppermost position, that is, with the lowermost one 5 in action, they should be returned to their original position for the delivery of the duplicate slugs cast from the succeeding line, so that they may be moved in the proper sequence to allow the duplicate slugs to be delivered to different galleys. Such return of the galleys may be effected in any desired manner—either manually or automatically. In the present instance this is effected manually, there being provided a cam-shaped arm 28 fixed to one end of a rock shaft 27 supported in the plate 15 and having at its opposite end an operating handle 26. The cam-shaped arm 28 is adapted to coöperate with a short rod 29 projecting rearwardly from the locking bar 21, the relation of the parts being such that as the shaft 27 is turned by the handle 26, the member 28 will urge the bar 21 toward the right against the action of its spring 22, and thus disengage it from the lug 20 projecting from the sector 18. In other words, when the sector plate 18 is rocked to its uppermost position, the bar 21 will engage beneath the lower projecting lug 20, and in order to permit

the return of the parts the bar is disengaged from the projecting lug by the operation of the handle 26.

The operation of the parts just described applies when the machine is casting duplicate slugs from the same composed line, and it will be understood that when it is desired to cast but one slug from each composed line the automatic mechanism for adjusting the galleys should be rendered inactive. This result is accomplished by pivoting the finger 23 to the first elevator 8 so that it may be swung out of engaging relation to the sector 18, as shown by dotted lines in Fig. 1.

In the accompanying drawings I have shown my invention merely in preferred form and by way of example, and it will be understood that many changes and modifications may be made therein which will suggest themselves to those skilled in the art without departure from its scope.

Having thus described my invention, its construction and mode of operation, what I claim and desire to secure by Letters Patent of the United States is, as follows:

1. In a typographical machine, the combination of slug casting mechanism, a plurality of galleys movable successively into operative relation thereto, and automatic means for effecting such movement of the galleys after succeeding casting operations; whereby the successive slugs will be delivered to different galleys, for the purpose described.

2. In a typographical machine, the combination of slug casting mechanism, a plurality of galleys movable successively into operative relation thereto, automatic means for effecting such movement of the galleys after succeeding casting operations, and devices for rendering said means active or inactive at will, for the purpose described.

3. In a typographical machine, the combination of slug casting mechanism, a line transporter movable toward and from the same, a plurality of galleys movable successively into operative relation to the casting mechanism, and means controlled by the line transporter for effecting such movement of the galleys.

4. In a typographical machine, the combination of slug casting mechanism, a line transporter movable toward and from the same, a plurality of galleys movable successively into operative relation to the casting mechanism, means controlled by the line transporter for effecting such movement of the galleys, and devices for rendering said means active or inactive, at will.

5. In a typographical machine, the combination of casting mechanism for producing duplicate slugs from the same composed line, a plurality of galleys, and automatic means for moving the galleys to bring them

successively into operative relation to the casting mechanism; whereby the duplicate slugs will be delivered to different galleys.

6. In a typographical machine, the combination of slug casting mechanism, and a plurality of superposed galleys, said galleys being movable vertically so that one or another may be brought into operative relation to the casting mechanism.

10 7. In a typographical machine, the combination of slug casting mechanism, a plurality of superposed galleys, and a fixed

chute leading from the casting mechanism to the galleys, the said galleys being movable vertically so that one or another may be 15 brought into operative relation to the fixed chute.

In witness whereof I have hereunto set my hand in the presence of two witnesses.

CHRISTIAN AUGUSTUS ALBRECHT.
